ABSTRACT

This is a combination holder for skis and ski poles which includes a pair of edge engaging members with a resilient anchoring element extending therebetween to securely hold said members against the edges of a pair of skis positioned in superposed relationship, each of said members being provided with a pair of pole gripping arms and having resilient means for holding the poles in said arms in substantially parallel relation to the skis on opposite sides thereof.

COMBINATION HOLDER FOR SKIS AND SKI POLES

A number of devices have been developed as a combination ski and ski pole holder, however, these combination units have been cumbersome and expensive to manufacture and in many instances have tended to scratch the skis and ski poles.

It is an object of my present invention to provide a ski and ski pole holder which is extremely simple and inexpensive to manufacture, while at the same time securely holding the skis and ski poles together without scratching or damaging either the skis or the poles.

It is a specific object to provide a pair of anchoring members which are resiliently held together to engage and anchor the edges of a pair of skis and wherein each of said members is provided with a pair of resilient pole engaging arms with means for positively capturing and holding the poles and skis together.

These and other objects and advantages of this invention will be apparent from the following description made in connection with the accompanying drawing wherein like reference characters refer to similar parts throughout the several views, and in which:

FIG. 1 is a front elevational view showing my holder in operative position holding a pair of skis and ski poles;

FIG. 2 is a transverse sectional view taken substantially on the line 2—2 of FIG. 1 with one of the ski poles removed; and

FIG. 3 is a sectional view taken substantially along the line 3—3 of FIG. 2.

A pair of skis 10 and a pair of ski poles 12 are illustrated in the accompanying drawings.

My ski and pole holder is shown in operative ski and pole holding position and includes a pair of anchoring members 15, each provided with a split center spacing ridge 17 separating a pair of edge receiving ski holding grooves 19. The grooves 19 respectively terminate in a pair of retaining ridges 21.

A pair of pole engaging arms 23 are formed in outwardly extending relation on the members 15 and in the form shown are integrally molded therewith as from a suitable plastic or nylon material. Each of the arms 23 has a pole receiving recess 23a formed therein to capture a ski pole when inserted therebetween. In order to positively hold the pole in captured relation a resilient stretchable locking loop 25 is provided. One end of the loop 25 is anchored to one of the ridges 21 and the other is removably received in a groove 21a in the other ridge 21 as best shown in FIG. 2.

The two anchoring members 15 are resiliently connected by means of the stretchable tying member 27. In the form shown the ends of the tying member 27 extend between the split sections of spacing ridges 17 and are respectively anchored to the members 15 as by the connecting knobs 29 which are received in anchoring recesses formed in the members 15.

The anchoring members 15 are initially attached to the skis by first inserting one of the skis 10 between opposed grooves 19 in the members 15 and the second ski

10 is thereafter inserted into the other pair of opposed grooves 19 by first placing one edge in one groove and thereafter spreading the other holder outwardly by stretching the tying member 27 to permit the other edge of the second ski to be received in the groove 19 of the second holder member 15. The two poles are then placed between the resilient arms 23 and snapped into the capturing grooves 23a and finally the elastic loops 25 are stretched around the poles to positively hold the same in captured relation between the arms 23 as illustrated.

My ski and ski pole holder is shown attached to one end of a pair of skis and ski poles and I have found that a single holder is sufficient to hold the ski poles in position, therefore, any suitable means for holding the other end of the skis together may be used such as a conventional elastic strap widely used for this purpose. It is, of course, also possible to use a second holder at the other end of the skis similar to my holder as described herein.

It will be seen that I have provided a relatively simple and inexpensive combination holder for skis and ski poles which is particularly designed to prevent damage to the skis and poles while securely holding the same together.

It will, of course, be understood that various changes may be made in the form, details, arrangement and proportion of the parts without departing from the scope of the invention, which generally stated, consists in the matter set forth in the accompanying claims.

What is claimed is:

1. A combination holder for skis and ski poles comprising
  - a pair of anchoring members each including a center ridge element and a pair of outer ridge elements respectively spaced outwardly from said center ridge element to define a pair of ski receiving grooves spaced apart by said center ridge element, resiliently stretchable tying means connected to the center ridge elements of the two anchoring members to tie the same together and securely hold the same in engagement with the edges of a pair of skis, said tying means being disposed between the skis and being of a thickness slightly less than the thickness of said center ridge elements, and
  - a pair of pole gripping arms disposed in outstanding relation on each of said anchoring members with means for capturing the poles in said arms in spaced substantially parallel relation to the edges of the skis.
2. The structure set forth in claim 1 and a pair of resiliently stretchable loop elements, one end of each loop being connected to one side of the respective anchoring members, each of said anchoring members having releasable attaching means on the other side thereof for respectively attaching the other ends of said pole surrounding loops to positively capture and surround a pole received between each pair of gripping arms.
